UNITED STATES PATENT OFFICE.

FREDERICK F. GAINES, OF SAVANNAH, GEORGIA, ASSIGNOR, BY MESNE ASSIGNMENTS, TO AMERICAN ARCH COMPANY, OF NEW YORK, N. Y., A CORPORATION OF DELAWARE.

LOCOMOTIVE-BOILER FURNACE.

1,138,060.

Specification of Letters Patent.

Patented May 4, 1915.

Application filed July 24, 1913. Serial No. 780,968.

To all whom it may concern:

Be it known that I, FREDERICK F. GAINES, a citizen of the United States, and a resident of Savannah, county of Chatham and 5 State of Georgia, have invented certain new and useful Improvements in Locomotive-Boiler Furnaces, of which the following is a specification.

My invention relates to improvements in 10 locomotive boilers and has special reference to improvements in the fire boxes of locomotives.

The object of my invention is to provide 15 a fire box construction particularly adapted for the burning of fuel-oil wherein and whereby the efficiency of the fire boxes and the economy of the fuel consumption shall be increased; to provide a fire box in which the gases of combustion shall be effectively 20 intermingled and mixed, through which their flow shall be retarded to a certain extent to permit the completion of combustion, and to cause the gases to effectively deliver heat to and through the walls of the fire box.

25 A further object of my invention is to provide a locomotive boiler fire box particularly adapted for the combustion of fuel-oil, and which shall effectively baffle the direct flow of the gases of combustion from 30 the ignition point to the flues and thus cause the gases to flow over substantially all of the interior surfaces of the fire box in their passage to the flues.

35 A further object of my invention is to provide such a fire box wherein air shall be added to and admixed with the gases of combustion after the fuel gases have been partly burned, and wherein the unburned non-gaseous products of combustion, if any, 40 shall be separated from the gaseous products before the gases enter the flues.

45 A further object of my invention is to provide a locomotive fire box wherein the advantages of an oil burner shall be combined with a baffle wall arranged in the path of the burning gases and spaced from the flue sheet.

50 A further object of my invention is to enhance and increase the efficiency of locomotive fire boxes of the oil-burning type.

Further objects and features of my invention will appear hereinafter.

My invention consists in a locomotive

boiler fire box having a refractory chamber closing its lower end and which extends 55 from the rear end of the fire box toward the forward end thereof, a transverse baffle wall arranged within the fire box rising from the forward end of the refractory chamber and spaced rearwardly from the flue sheet, said 60 chamber being adapted to serve as a fuel-oil combustion chamber and the wall serving to prevent the direct flow of the burning gases from the combustion chamber to the flues.

My invention further consists in a fire 65 box equipped as above stated, the baffle wall being provided with air inlet passages adapted to admit air into the fire box above the refractory combustion chamber whereby the efficiency and economy of the fuel is en- 70 hanced.

A further object of my invention is to provide a locomotive boiler fire box particularly adapted for burning fuel-oil and having an auxiliary chamber in direct communication with the flues and separated from the main combustion chamber by a refractory wall, and means for admitting air to the gases of combustion between the main and the auxiliary combustion chambers. 75

My invention further consists in the several arrangements and combinations of parts, and in the features of construction, by which the above and other objects are attained, and all as hereinafter described and 80 particularly pointed out in the appended claims.

My invention will be more readily understood by reference to the accompanying drawings forming part of this specification 85 and in which:

Figure 1 is a vertical, longitudinal, central section of a locomotive boiler fire box embodying my invention; Fig. 2 is a transverse, vertical section of the fire box on the 95 line 2-2 of Fig. 1; and Fig. 3 is a horizontal section of the cross wall on the line 3-3 of Fig. 1.

In the use of fuel-oil as a fuel in locomotives, it has been found that even with the best attainable nozzles or burners, and with the use of locomotive fire boxes as commonly equipped, the efficiency of the fuel is not perfect, for the reason that the air and fuel are not thoroughly intermingled and mixed 105 and consequently some of the fuel enters

the flues unburned and some of the air escapes from the fire box without being combined with the fuel.

It is my particular object to provide a fire box in which the combustion of the fuel will be substantially perfect and I accomplish this result by providing an ignition or combustion chamber, for the oil, which is lined upon its bottom and sides with fire 5 brick adapted to become highly heated and retain the heat for the purpose of gasifying the oil, and combining with this combustion chamber a transverse refractory wall arranged between the forward end of the combustion chamber and the flues, and serving to prevent the direct flow of the gases to the flues and cause them to rise upwardly through the combustion chamber in contact with the side walls thereof and flow longitudinally along the crown sheet, where they are adapted to deliver their heat through the walls of the combustion chamber into the water of the boiler. For the purpose of enhancing these results, I provide the wall 10 with air-inlet passages or openings through which air enters from beneath the fire box into the fire box itself, being heated in its passage through the wall and being delivered into the body of the burning gases as 15 the flow in contact with the baffle wall in their passage to the flues.

While I have shown the refractory combustion chamber as being wholly within the lower part of the fire box it should be understood that this feature may be changed or varied without departing from the spirit of my invention, that is, it may be arranged below the lower edge of the fire box, but in such condition that the lower part or the 20 end of the fire box is closed against the entrance of air, excepting at certain predetermined points. I also combine with the other features of my invention what may be termed "a cinder outlet or discharge" arranged in the floor of the auxiliary combustion chamber between the baffle wall and the flue sheet and adapted to facilitate the withdrawal or removal of any fuel particles or cinders which may collect in this chamber. 25 A locomotive boiler fire box A, as illustrated in the drawings, is made up of a flue sheet a^1 , a rear sheet a^2 , a crown sheet a^3 , and side sheets a^4 . Flues a^5 lead forward into the boiler from the flue sheet and the rear sheet is usually provided with a fuel door or opening a^6 . In the lower part of the fire box I provide an open-topped combustion chamber B, closed on its lower side by a refractory floor b^1 . The chamber B 30 extends from the rear end of the fire box toward the forward end thereof, and its forward end is spaced rearwardly from the flue sheet, it occupying the space usually occupied by the grate in a coal-burning fire box. The chamber is completed by refrac-

tory side walls b^2 , a forward wall b^3 , and a rear refractory wall b^4 . The rear wall is in contact with the rear sheet of the boiler and rises above the side walls b^2 . It serves to receive the impact of the oil which is injected into the combustion chamber through the opposite end b^5 by the oil burner C. The lower wall or floor b^1 is maintained in position by a plate b^6 which is secured to the lower edge of the fire box. I close the space 70 between the forward end of the combustion chamber and the flue sheet by means of a floor a^7 arranged somewhat above the lower edge of the fire box and above the burner C, and upon the rear end of this floor, adjacent 75 to the forward end of the combustion chamber, I erect a transverse refractory wall D. I extend this refractory wall across the fire box at this point and thereby divide the fire box itself into an auxiliary combustion 80 chamber a^8 , between the wall and the flue sheet, and a main combustion chamber a^9 between the rear end of the fire box and the wall D. This wall serves as a baffle to prevent the direct flow of the gases of combustion from the chamber B to the flues and forces these gases to rise through the fire box in contact with the walls and flow along the crown sheet, thereby delivering their heat to the water in the boiler. The forward 85 wall b^3 of the combustion chamber B is provided with a central opening b^6 through which the burner C projects. This opening is considerably larger than the burner for the purpose of permitting the injection of 90 the oil through the burner to draw air into the combustion chamber. A certain quantity of air is thus supplied for the combustion of the oil through this opening b^6 , and for the purpose of completing the burning 95 of the oil I provide vertically extending air passages d^1 , in the baffle wall D, which extend from the lower end thereof and open into the main combustion chamber a^9 adjacent to the upper edge of the wall. The 100 plate a^7 is provided with suitable openings to permit the air to enter from beneath the plate into said air passages or channels d^1 and thus enter the fire box. For the purpose 105 of causing the air to intermingle and mix with the rising fire box gases, I provide the top of the wall with a rearwardly projecting coping d^2 beneath which the air enters from the passages d^1 , and is caused by this coping to intermingle and mix with the fire box 110 gases which rise through the fire box adjacent to the baffle D.

I preferably build the baffle wall D of a plurality of horizontal rows of fire bricks d^3 . These bricks are provided on their upper 115 sides with central projections or tongues d^4 and on their lower sides with complementary grooves d^5 and by means of this construction the several rows of bricks are interlocked together. For the purpose of 120

130

maintaining this wall in position upon the plate a^7 , I provide an upwardly projecting ledge d^8 at the rear end of the plate against which the rear face of the lower row of 5 bricks contacts, and I provide a buck stay plate d^7 conformed to and with the forward face of the wall secured rigidly at its lower end to the plate a^7 . This buck stay plate 10 preferably extends substantially the full height of the wall and the upper row d^8 of the bricks d^7 is secured to the upper part of the buck stay plate by bolts d^9 .

The auxiliary combustion chamber a^8 serves to retard and hold any solid particles 15 of fuel which may be carried over the baffle wall for as the gases of combustion enter the auxiliary combustion chamber they expand to fill the chamber and thus reduce their rate of travel and are thereby caused 20 to deposit their burden, if any, of unburned fuel.

For the purpose of conveniently removing any cinders or unburned fuel particles which may collect in the auxiliary combustion 25 chamber, I provide in the floor thereof a normally closed cinder-opening E . This opening enters substantially the center portion of the floor of the auxiliary combustion chamber a^8 , and is provided with a cover e^1 at its lower end, which is normally closed, and prevents the entrance of air at this point. The cover e^1 is hinged in position and is adapted to be swung to one side to 30 permit the removal of the material which collects within the hopper E . For the purpose of causing any particles which may collect in the lower end of the auxiliary combustion chamber a^8 to enter the hopper E , I provide this chamber with a hoppered bottom by filling in the corners thereof with refractory material providing inclined surfaces e^2 extending from the edges of the hopper E to the side walls of the auxiliary combustion chamber.

45 The forward wall b^2 of the combustion chamber B is protected by means of a plate b^7 which is secured at its lower edge to the lower plate b^6 and at its upper edge to the rear end of the floor plate a^7 . The upper edge of this plate b^7 extends above the plate a^7 and provides the projection d^8 heretofore mentioned.

In the use of my invention, the combustion chamber B , once having been heated, 55 the oil which is projected thereinto by means of the burner C is gasified by its contact with the heated walls and floor thereof, and is partly consumed by the air which enters through the opening b^8 ; it rises thence 60 through the fire box in contact with the walls thereof and with the baffle wall D , and at the upper edge of this baffle wall D it is combined and intermingled with the air which enters through the air passages d^1 in 65 the wall D . The air is projected upwardly

through these passages d^1 with considerable force by reason of the fact that they are arranged in close proximity to the vertical wall or plate b^7 , and as the locomotive moves forward the air beneath the fire box, in striking this vertical plate b^7 , is forced upwardly and forced into and through the passages d^1 into the combustion chamber. This serves to cause the incoming air to be thoroughly intermingled and mixed with the rising fire 75 box gases and thereby affect the complete combustion of the fuel. The height of the wall D is determined by the details of shape and construction of the fire box in which it is being installed, but usually it is best arranged to rise somewhat above the middle of the height of the fire box leaving a passage a^{10} above the wall which is substantially a third of the whole height of the fire box.

As many modifications of my invention 80 will readily suggest themselves to one skilled in the art, I do not limit or confine my invention to the specific structures herein shown and described.

I claim:—

1. A locomotive boiler fire box closed at its lower end and having a refractory lined combustion chamber in the rear part thereof, an oil burner adapted to project oil into said combustion chamber, a refractory cross wall rising within the fire box at the forward end of the combustion chamber and spaced rearwardly from the fire sheet, preventing the direct flow of the products of combustion from the combustion chamber to the flues, and a normally closed opening in the lower part of the fire box, arranged between the cross wall and the fire sheet.

2. A locomotive fire box closed at its lower end and having a refractory lined combustion chamber in the rear part thereof, the forward end of the combustion chamber being spaced rearwardly from the fire sheet and provided with a burner opening, a vertical cross wall rising within the fire box substantially above said burner opening and provided with air-admission passages ending in flared air admission inlets opening through the rear face of the wall, as and for the purpose specified.

3. A locomotive boiler fire box in combination with a refractory bottom closing therefor provided in its rear part with a depressed combustion chamber, the forward wall of said chamber being spaced rearwardly from the fire sheet and provided with a burner opening, a refractory cross-wall rising within the fire box above said burner opening extending from side to side of the fire box and provided with air channels rising within the wall and which are flattened in the plane of the wall and adapted to discharge heated air into the fire box through the rear face of the wall.

4. A locomotive boiler fire box, closed at

its lower end and having a refractory combustion chamber in the rear part thereof, the forward wall of said combustion chamber containing a burner opening, a refractory cross wall rising within the fire box above said burner opening and provided at its upper edge with a rearwardly projected ledge or coping and having oval air passages rising within the wall adapted to discharge heated air through the rear face of the wall below said ledge or coping.

5. A locomotive boiler fire box, closed at its lower end and having a refractory combustion chamber in the rear part thereof, the forward wall of said combustion chamber being spaced rearwardly from the flue sheet and provided with a burner opening, a refractory cross wall rising within the fire box substantially above said burner opening, said wall being provided with vertically extending air admission passages having flared outlets as and for the purpose specified.

10. A locomotive fire box closed at its lower end and having a refractory lined combustion chamber in the rear part thereof, the forward wall of the combustion chamber being spaced rearwardly from the flue sheet and provided with a burner opening, a refractory cross wall rising within the fire box substantially above said burner opening, said wall being provided with vertically extending air admission passages having flared outlets as and for the purpose specified.

15. A locomotive boiler fire box, closed at its lower end and having a refractory combustion chamber in the rear part thereof, the forward wall of said combustion chamber being spaced rearwardly from the flue sheet and provided with a burner opening, a refractory cross wall rising within the fire box above said burner opening and provided at its upper edge with a rearwardly projected ledge or coping and having oval air passages rising within the wall ending in

flared air openings positioned to discharge heated air through the rear face of the wall below said ledge or coping.

25

6. A locomotive fire box closed at its lower end and having a refractory lined combustion chamber in the rear part thereof, the forward wall of the combustion chamber being spaced rearwardly from the flue sheet and provided with a burner opening, a refractory cross wall rising within the fire box substantially above said burner opening, said wall being provided with vertically extending air admission passages having flared outlets as and for the purpose specified.
